(57) **CLAIM**

The ornamental design for a security light canopy housing, as shown and described.

DESCRIPTION

FIG. 1 is an upper perspective view of a security light canopy housing design;

FIG. 2 is a lower perspective view of the security light canopy housing design of FIG. 1;

FIG. 3 is a left side view of the security light canopy housing design of FIG. 1;

FIG. 4 is a right side view of the security light canopy housing design of FIG. 1;

FIG. 5 is a top view of the security light canopy housing design of FIG. 1;

FIG. 6 is a bottom view of the security light canopy housing design of FIG. 1;

FIG. 7 is a front view of the security light canopy housing design of FIG. 1; and,

FIG. 8 is a rear view of the security light canopy housing design of FIG. 1.

The broken lines show portions of the security light canopy housing that form no part of the claimed design.

1 Claim, 8 Drawing Sheets
